United States Patent Office.

CHARLES T. PALMER, OF NORWICH, CONNECTICUT.

Letters Patent No. 82,024, dated September 8, 1868.

IMPROVED SPICE-BOX.

The Schedule referred to in these Letters Patent and making part of the same.

TO ALL PERSONS TO WHOM THESE PRESENTS SHALL COME:

Be it known that I, CHARLES T. PALMER, of the city of Norwich, of the county of New London, of the State of Connecticut, have invented a new and useful Improvement in Spice-Boxes or Cans; and do hereby declare the same to be fully described in the following specification, and represented in the accompanying drawings, of which—

Figure 1 is a vertical section of a spice-box or can provided with my improvement.

Figure 2 is a top view of the can.

Figure 3 is a top view, and

Figure 4 a section of the cap for the holes of discharge of the cover-end or head of the can.

On June 23, 1868, Letters Patent of the United States of America, for a spice-can, were granted to me. My present invention involves the principle of that, and contains an important improvement or addition.

The said can or box is for the purpose of holding spices or other articles or powdered matters, it being so formed that, by removal of the cap, the spice or powdered material may be shaken out through holes in the cover or head of the can.

The spice-box or can, as patented by me, was made not only with a series of perforations or holes in its end or cover, but it had therein a cavity and a circumscribing annular head, the said cavity being to receive a flat disk or plate, to serve as a cap to the holes.

In carrying out my present improvement, I make the end or head of the cover with an annular groove surrounding the series of holes, and I make the cap or disk with a corresponding annular bead, to extend into and fit to the said annular groove; or, what is the same, I make the end or cover with an annular bead, as in my patented can, and, in connection therewith, I make the cap or cover with an annular groove, to receive the said bead. The cap of my patented can had no such bead, but was a perfectly flat disk.

In such drawings, A denotes the body of the box, and B the cover, the series of holes of discharge being shown at a a, &c. The circular or annular groove is seen at b b. The cap or disk, C, is represented as made with an annular bead, c c, whose diameter and cross-section correspond with those of the groove b, it being intended, when the cap is in place, that the bead shall enter and completely fill the groove. An equivalent to the groove of the cover or end, and the annular bead in the cap, would be the arrangement of the bead on the cover or end of the box, and the groove in the cap or disk.

The advantages of constructing the cap with either an annular bead or a groove, to fit upon a corresponding groove or bead, formed in or on the cover or end of the box, is that it renders the cap stronger, insures a better fit of it, operates much better to prevent waste of the spice or powdered material when put up in the box, and while the box is in transit, and causes the cap to be held in place to much better advantage, particularly when the outer casing of paper is pasted on the can.

My improvement also enables the cap to be sealed down, if necessary or desirable, by a sealing of wax or other proper material or composition, introduced into the groove.

I therefore claim, in the spice-box or can, as made with a series of holes in its cover or end, or as having a disk or cap to cover such holes, the constructing both the cover or end or head of the box and the disk, with an annular groove in the one, and a corresponding annular bead to project from the other, and to fit to or into such groove in manner substantially as described.

CHARLES T. PALMER.
